WEFT DETECTOR AND STOP MOTION FOR
WEAVING LOOMS

Thomas Hindle, Blackburn, England

Application September 21, 1950, Serial No. 185,990
In Great Britain September 25, 1949

5 Claims. (Cl. 139—370)

1

This invention relates to looms for weaving and more particularly to improvements in weft detectors and loom stop-motions.

The object of the invention is to provide an improved weft detector which is sensitive to the tension of the weft as this is laid in the warp shed by the moving shuttle.

According to the invention, when the shuttle enters the shed, the weft is caused to loop round a sensitive detector pin temporarily positioned closely adjacent to or actually amongst the selvage warp threads near the fell of the cloth, the pull exerted by the weft on the said pin being utilised to close the contacts of an electric switch against the pressure of a light spring acting to open them.

The invention is illustrated in and will be described with reference to the accompanying drawings. In these drawings—

Fig. 1 is a front elevation, partly in section, of the improved weft detector, which is shown in the detecting position in relation to the selvage of the cloth being woven;

Fig. 2 is a partial cross-section through a loom showing one suitable form of mechanism for actuating the arms which support the weft detectors;

Fig. 3 is an electric circuit diagram illustrating the action of the detector switches; and

Fig. 4 is a timing diagram based on one revolution of the loom crankshaft.

Referring to Fig. 1, which illustrates the weft detector and the manner in which it functions, an approximately vertical detector-pin 1, tapered or pointed at its lower end is suitably clamped by screws 2^b in a holder 2^a, which is pivoted at 2 on the inner end of a horizontal holder-bar 3, fixed stops 4 and 4^a being provided to restrict the rocking movement of the holder 2^a and the detector-pin 1 to a small angle.

An electric switch 5 is mounted on the outer end of the holder-bar 3, preferably adjustably, as for instance by means of the collar 5^a, which forms part of the switch casing, and the screw 5^b. The switch 5, which may be of any suitable type provided with a light spring acting to separate the switch contacts, is actuated by the detector-pin through a push-rod 6, the inner end of which bears on the detector-pin, or as shown on its holder 2^a, a short distance above the pivot 2, and the outer end of which bears on the plunger 5^c of the switch 5. The push-rod 6 slides in bushes 3^b inserted in a central passage 3^a in the holder bar 3.

When the weft pull is absent on the detector-

pin 1 the contacts of the switch 5 are opened by the switch-spring, and the detector-pin, by reason of its unbalanced weight in relation to pivot 2, assumes its natural position, as shown by the centre-line a—b, in which the lower end of the holder 2^a rests against the stop 4^a.

The pull of the weft W^t looped round the detector-pin at the picking end of the loom displaces the bottom end of the pin in the direction 10 of the moving shuttle (indicated by arrows in Fig. 1) with the result that the pin then rocks to the position shown in Fig. 1, corresponding to centre-line c—d. Such displacement is transmitted on a reduced scale by the push-rod 6 to the plunger 5^c of the switch 5 so as to close the switch contacts, which then remain closed provided that the weft continues to exert the necessary pull on the detector-pin 1 throughout the remainder of the shuttle's flight.

When the weft has pulled the detector pin 1 to position c—d, so that the holder 2^a bears firmly against stop 4, the pin in such position is rigidly supported and is well adapted to withstand without further displacement any snatch or abnormal pull exerted by the weft.

The improved weft-detector possesses, therefore, the incidental advantage of preventing, in well-known manner, the cloth selvage being pulled in unevenly by irregular weft tension.

30 In Fig. 1, the woven cloth is indicated in cross-section at C, E being one selvage. W^p represents the warp threads forming the shed, through which the weft W^t is being laid by the shuttle travelling in the direction indicated by the arrows.

35 In Fig. 2, the weft W^t is shown extending between the cloth-fell F and the shuttle S passing through the shed formed by the warp threads W^p. The weft W^t loops round the detector-pin 40 1. The slay is shown in solid lines at L^b in its fully back position, in dotted lines at L^f in its fully forward position.

The horizontal holder-bar 3, is clamped by a screw 7^a approximately midway in its length at 45 the end of an arm or lever 7, secured so as to rock with a rocking shaft 8, which is parallel to and is supported in bearings 8^a fixed on the front-rest R of the loom.

A mechanism constructed and arranged as so far described is provided at each selvage side of the loom and both arms 7 are given a suitable rocking movement in synchronism with the forward and backward movements of the slay. The rocking shaft 8 may be actuated through any 50 suitable mechanism connected to the slay or its

swords, or by a cam or cams revolving at crank-shaft speed. In the case of very wide looms, the rocking shaft 8 may be in two parts, each actuated independently, but in unison.

Referring to Fig. 2, as the slay retires from its forward position L^f in anticipation of the next picking operation, the arms 7 swing down to carry the detector-pins into their detecting position, that is, as shown in Fig. 1 and in full lines in Fig. 2, closely adjacent to or actually amongst the selvage warp threads near the fell F of the cloth, with the bottom or pointed end projecting slightly below the plane of the bottom shed.

The detector-pin 1 remains in this position until at a suitable time as the slay is again advancing towards its front position, shown by dotted lines at L^f, the arms 7 swing up, first withdrawing the engaged detector-pin in an upward direction from the weft loop, and then swinging both arms and detectors upward and forward out of the way of the slay which is then advancing to beat up the weft. The time at which the detector-pin 1 is withdrawn from the weft loom does not occur until after the shuttle has arrived in the opposite box, so that the detector is sensitive to the tension of the weft during the major and final portion of the shuttle's passage across the slay.

One suitable arrangement of actuating the rocking shaft 8 and hence the arms 7 fixed thereon is shown in Fig. 2. In this arrangement the loom crankshaft 9 is provided with a negative cam or cams 10, co-acting with roller 11^b on a follower-lever 11, pivoted at 11^a on the loom framing. The displacement of the lever 11 by the cam 10 is transmitted by a link 12 to a two-arm lever 13 which is pivoted at 13^a on the loom framing. A spring 16 anchored at one end to the frame of the loom and at the other end to one arm of the lever 13 acts on the latter to maintain the roller 11^b carried by the follower-lever 11 in contact with the cam 10.

The upper arm of the lever 13 is connected by link 14 to lever 15 which is fixed to the rocking-shaft 8, on which the arms 7 are secured.

Instead of employing a negative cam 10 for actuating the follower-lever 11 a positive cam may be employed in which case the spring 16 is not required.

As applied to a wide loom in which the slay movement includes appreciable "dwell" in or near the back position to allow of the shuttle's passage through the shed, the profile of the cam 10 is preferably such that the arms 7 remain up for about one-quarter of the crankshaft's revolution and remain down for about one-half, the remaining two-eighths sufficing for the up and down movements.

The arms 7 supporting the weft-detectors are adjustable along their shaft or shafts 8 to suit the exact width of cloth being woven. A flexible cable 5^c connects each swinging switch 5 to a terminal box or plug 5^d mounted underneath the front-rest R.

The details of the mounting and actuation of each switch may be varied if desired. For example the switches may be mounted on or below the front-rest and be actuated through mechanical linkage from the detector-pins 1.

The weft-detector mechanism hereinbefore described can be used either to close an electric circuit or, as is preferred, to maintain an electric circuit which would otherwise be broken, as an indication that the weft is intact from the loop round the detector-pin 1 to the moving shuttle.

tle. It may be employed to indicate whether the weft is intact right across the loom's reeded width at or just before the time when the shuttle completes its passage, or at any desired earlier stage in the shuttle's flight after the weft should normally have looped round and actuated the detector-pin at the picking end. Such indication may be adapted to control any form or loop stop motion so as to cause the loom to be stopped in the event of weft failure.

The weft detector switches 5 act by controlling the circuit of an electro-magnet, the basic principle being that such electro-magnet must be energised, or continue to be energised at the crucial moment if the loom is to continue running. Thus if the weft fails to make or to maintain the circuit of the electro-magnet, the loom stops. The loom also stops should the electric supply for the detector circuit fail for any reason.

The aforesaid electro-magnet may be controlled by a pair of weft detector switches, operating in combination with a cam-actuated weft try-switch, such cam revolving at slay crank-shaft speed. Alternatively, the weft try-switch 25 may be actuated by a cam or cams mounted on any other shaft, or by an oscillating cam or equivalent linkage connected to the slay or slay swords, the essential requirement being that the weft try-switch shall open and close at the desired times in each successive revolution of the loom crankshaft. The two weft detector switches and the weft try-switch are all three connected in parallel with the electro-magnet and a suitable source of electric current. Fig. 3 shows such a circuit arrangement in diagrammatic form, the weft-actuated detector switches 5 being connected in parallel with the cam-actuated weft try-switch 17, and then in series with the electro-magnet 18. The cam-actuated weft try-switch 17 maintains the circuit for part of the crankshaft's revolution, but opens the circuit at any desired point during the period the shuttle is normally passing through the shed, during which period one or the other of the detector switches 5 normally should be closed due to the pull of the weft exerted on the corresponding detector-pin 1.

In Fig. 4 which shows a timing diagram typical for a wide loom, I represents the crank position at beat-up when the slay is fully forward and V represents the crank position when the slay is fully back. The arms 7 remain up out of the path of the reed from VIII to II. From II to III the arms are lowered to carry the detector-pins 5 into their detecting position, where they remain until VII. From VII to VIII, the arms are lifting. The picking impulse normally commences at III and the shuttle passage takes place from IV to VI. The weft try-switch opens at about V and remains open until about VI, after which it re-closes and remains closed for the remainder of the cycle.

If the weft runs out or breaks so that the appropriate detector switch 5 is not closed when the weft try-switch 17 opens the circuit at about V, then the electro-magnet is promptly de-energised and the loom thereby caused to be stopped automatically. Similarly, if the weft is intact when the weft try-switch opens at about V, but subsequently fails before it re-closes at about VI, then the appropriate detector-switch 5 opens with the result that the electro-magnet is de-energised and the loom thereby caused to be stopped automatically.

I claim:

1. A weft detector motion for controlling the stop motion of a loom comprising the combination with an electric switch of a sensitive detector-pin, means for temporarily positioning said pin in close relationship to the selvage warp threads near the fell of the cloth during the passage of the shuttle across the slay, and a member between said pin and switch for controlling the switch, the movement of the shuttle causing the weft to loop around the detector pin and exert a pull thereon to move it into a position to operate said member to close the switch and maintain the switch closed so long as the pin remains in close relationship to the selvage warp threads and the weft continues to exert a pull on the pin.

2. In a weft detector motion as in claim 1, the combination with the sensitive detector-pin of a pivot on which it is mounted in a slightly unbalanced condition, and wherein said member comprises a push rod adapted to be engaged by the detector-pin when it is moved out of its neutral position by the pull of the weft, and said electric switch has spring controlled contacts which are closed by the movement imparted to the push rod by the detector-pin due to the pull of the weft, and including an electric circuit containing the switch and controlling the stop motion of the loom.

3. In a weft detector motion as in claim 2, the combination with the sensitive detector-pin, of a holder rotatably mounted on said pivot and in which the detector-pin is adjustably mounted, a holder-bar in which the push rod is slidably mounted, the holder being pivotally mounted at

the end of the holder bar so that the holder and the pin are out of balance, and a housing for the switch at the opposite end of the holder bar to that at which the holder for the pin is pivotally mounted.

4. In a weft-detector motion as in claim 3, the combination with the detector-pin, the holder therefor, and the holder bar of a rocking arm in which the holder bar, is carried, and a cam making one revolution for each revolution of the crank shaft of the loom, said cam controlling the rocking arm to lower the detector-pin into the detecting position in close relationship to the selvage warp threads and to raise it therefrom at the appropriate points in the weaving cycle of the loom.

5. In a weft detector motion as in claim 4, the combination with the detector-pin, the holder therefor, the holder bar, the rocking arm and the actuating cam of a pivoted follower-lever which is actuated by the cam, a rotatably mounted shaft on which the rocking arm is affixed and a lever and link mechanism connecting the follower-lever to the shaft.
